UNITED STATES PATENT OFFICE.

FRANK F. LANDIS, OF WAYNESBOROUGH, PENNSYLVANIA.

TRACTION-ENGINE.

SPECIFICATION forming part of Letters Patent No. 355,939, dated January 11, 1887.

Application filed April 27, 1886. Serial No. 200,252. (No model.)

To all whom it may concern:

Be it known that I, FRANK F. LANDIS, a citizen of the United States, residing at Waynesborough, in the county of Franklin and State of Pennsylvania, have invented certain new and useful Improvements in Traction-Engines, of which the following is a specification, reference being had therein to the accompanying drawings.

10 This invention relates particularly to the construction of the master gear-wheel and its connections with the frame; and the objects of my improvement are to give to the master-gear a very large bearing-surface, to have its gear-teeth always well oiled, and to have its bearing-surfaces and gears well protected from dust. I accomplish these objects by the construction illustrated in the accompanying drawings, in which—

20 Figure 1 is a rear view of a traction-engine provided with a master gear-wheel and connections constructed in accordance with my invention. Fig. 2 is a side view, partly in section, of a master gear-wheel and its connections with a traction-engine, having one of its traction-wheels in a dotted outline. Fig. 3 represents a portion of the master-wheel connected in a modified manner with the housing and a portion of one of the traction-wheels of 25 the engine.

30 Similar letters refer to similar parts throughout the several views.

A represents the rear portion of the boiler, B the traction-wheels, and C the axle thereof. 35 Upon the sills G are secured the housings or the part of the frame represented at D, and to the side of said housings is attached a plate, E, having laterally a circular flange, E, the interior of which is turned true to receive the 40 peripheral edge of the master-gear F. I stated that the plate carrying the flange E is attached to the housings. This is simply to facilitate the renewal of the bearing-flange; but it may be made integral with said housings, and is 45 thus shown at E in Fig. 3.

The master-gear F is simply a cogged rim, having its sides and periphery or outer end of the teeth turned true to form a journal which fits into the interior of the circular flange or 50 case E. The master-gear is thus made without a hub and arms or spider, and consequently lighter than heretofore. To retain the mas-

ter-gear in proper central position upon its retaining-flange E, an annular flat plate or hollow disk, E², is secured to the outer side of the flange E, and it also retains the lubricating-oil upon said flange.

To connect the master-gear with the traction-wheel, or with the mechanism between them, it is provided, as shown in Figs. 1 and 2, with lugs e, transversely carrying a pin, e², that passes through one end of the link L, and through the opposite end of said link passes a pin, i, projecting from one side of a gimbal-ring, I, and from the opposite side of said gimbal-ring, at a point ninety degrees from the pins i, (four pins being used,) are lugs or pins i², that pass through one end of links K, and the opposite ends of said links pass through lugs M on the periphery of the center wheel of a 70 compensating gear, H, connected with the traction-wheel.

The above-described mode of supporting and revolving a gear-wheel upon its periphery may not seem the best; but in practice it shows good 75 results, especially as the resistance to said wheel is connected therewith at two opposite points on the inside of the rim. There is but little resistance upon the bearing-surfaces between the wheel F and the case E, except the 80 weight of said wheel and the resistance due to the thrust of cog-wheels meshing together.

Although I prefer to have the compensating gear upon the main axle, as the parts can be made larger, the compensating gear may be 85 upon the counter-shaft nearly on top of the boiler, as shown in Patent No. 266,698, granted to me October 31, 1882. The traction-wheel can then be closer to the master-gear and be connected thereto by six coiled or rubber 90 springs, one end of which bears against lugs projecting from the traction-wheel and the other against lugs projecting from the master-gear, and thus carry the entire weight of the rear end of the engine, and the springs N under the axle may be dispensed with, and the bearings P and guides in the housings would only serve to keep the axle and allow it to play in a vertical plane.

In place of having the housings provided 100 with a lateral flange, E, encircling the periphery or the ends of the cogs of the master-gear, the flange E may, as shown in Fig. 3, enter a circular groove cut in the side of the master-

gear, and the latter be entirely or partly supported by said flange.

Although I prefer to make the master-gear without spokes, so as to be lighter, it may have 5 spokes united to a hub having a large central opening, through which the axle may play up and down.

Having now fully described my invention, I claim—

10 1. In a traction-engine, the combination of a traction-wheel, a spokeless master-gear, and mechanism to yieldingly connect said traction-wheel and gear with the frame or housings of said engine, and a flange projecting from said

frame or housings and supporting said master-gear, substantially as described.

2. The combination of a traction-wheel, a hubless master-gear, and mechanism for connecting said traction-wheel and master-gear with the frame or housings of said engine, and 20 a flange projecting from said housings, substantially as and for the purpose described.

In testimony whereof I affix my signature in presence of two witnesses.

FRANK F. LANDIS.
